CLAIM

The ornamental design for set of handles for an article of cookware, as shown and described.

DESCRIPTION

FIG. 1 is a front perspective view of a set of handles for an article of cookware showing my new design;

FIG. 2 is an enlarged perspective view of one of the handles shown in FIG. 1;

FIG. 3 is a top view of the handles shown in FIG. 1;

FIG. 4 is a bottom view of the handles shown in FIG. 1;

FIG. 5 is a side view of the handles shown in FIG. 1;

FIG. 6 is another side view of the handles shown in FIG. 1;

FIG. 7 is a front view of the handles shown in FIG. 1; and,

FIG. 8 is a rear view of the handles shown in FIG. 1.

The part of the drawings shown in phantom lines depicts the environment of my new design and forms no part of my design.
